Carl McNeely,

BY *Victor J. Evans*

ATTORNEY

UNITED STATES PATENT OFFICE.

CARL MCNEELY, OF POLK, NEBRASKA, ASSIGNOR OF ONE-THIRD TO CLINTON LEWIS AYRES, OF POLK, NEBRASKA.

RADIATOR.

1,374,021.

Specification of Letters Patent. Patented Apr. 5, 1921.

Application filed January 16, 1918. Serial No. 212,088.

To all whom it may concern:

Be it known that I, CARL MCNEELY, a citizen of the United States, residing at Polk, in the county of Polk and State of Nebraska, have invented new and useful Improvements in Radiators, of which the following is a specification.

This invention relates to radiators such as are now commonly used in connection with the water cooling systems of internal combustion engines, the object of the present invention being to produce a radiator embodying top and bottom headers and connecting water tubes in communication with said headers, the construction of the radiator embodying walls of such formation and relation to each other as to present efficient cooling surfaces of large area in small space as well as prevent the bursting or fracture of said walls when the water freezes in the radiator.

A radiator constructed in accordance with the present invention will maintain itself in a water-tight condition notwithstanding the frequent freezing of water therein, thus greatly reducing the expense of motoring and the trouble and annoyance incident to the fracture or injury of the radiator and frequent repairs, due to freezing.

With the above and other objects in view, the invention consists in the novel construction, combination and arrangement of parts, herein described, illustrated and claimed.

In the accompanying drawings:—

Figure 1 is a front elevation of a radiator embodying the present invention.

Fig. 2 is a vertical transverse section through the same.

Fig. 3 is a horizontal cross section on the line 3—3 of Fig. 2.

Figs. 4 to 8 inclusive are cross sections through different forms of water tubes.

The radiator contemplated in this invention comprises top and bottom headers 1 and 2, respectively, and water tubes 3 which ordinarily extend vertically between the top and bottom headers and are in constant communication therewith.

In carrying out the present invention, the top header 1 is provided with inwardly dished curvilinear front and rear walls 4 and

5, respectively and also comprise an inwardly dished curvilinear bottom wall 6. The top wall 7 is shown as flat so that the appearance of the radiator will be approximately the same as the appearance of the present day automobile or motor truck radiator. If desired however the top wall 7 may also be inwardly dished and curvilinear in cross section.

The bottom header 2 comprises a bottom wall 8 which is inwardly dished and curvilinear in cross section and said bottom header also comprises front and rear walls 9 and 10 which are inwardly dished and curvilinear in cross section.

Each of the water tubes 3 connecting the top and bottom headers and communicating therewith for transferring the water from one header to the other, is also formed with a plurality of inwardly dished and curvilinear walls 11 the object and purpose thereof being the same as the inwardly dished walls of the top and bottom headers. As indicated in Figs. 4 to 8 inclusive, each of the tubes 3 may be of various shapes in cross section, the essential feature being that each tube comprises one or more inwardly dished walls which is capable of being pressed outwardly when water freezes therein without fracturing or injuring such wall and the tube of which it forms a part.

From the foregoing description taken in connection with the accompanying drawings it will now be understood that each of the water circulating compartments of the radiator embodies one or more inwardly dished walls preferably curvilinear in cross section. Such a wall presents a larger cooling area than a flat surface and allows for the expansion of the water as it freezes and subsequently enables ice to thaw without in any way injuring said wall or walls of the water compartment.

I claim:—

1. In a radiator, the combination of a top header, a bottom header, and a series of water tubes connecting said top and bottom headers and communicating therewith, said top and bottom headers constituting water compartments and each of said compartments comprising an inwardly dished wall

thereby presenting an enlarged cooling surface within a given space and allowing such portion of each compartment to bend outwardly under excessive internal pressure.

- 5 2. In a radiator, the combination of a plurality of water compartments including a top header, a bottom header, and a plurality of water tubes connecting said top and bot-

tom headers and communicating therewith, each of said headers embodying a plurality 10 of inwardly dished walls of curvilinear formation in cross section as and for the purpose set forth.

In testimony whereof I affix my signature.

CARL McNEELY.
